UNITED STATES PATENT OFFICE

119,202

DESIGN FOR A WHISKY FLASK

Darrell E. Briner, Winchester, Ind., assignor to Ball Brothers Company, Muncie, Ind., a corporation of Indiana

Application November 24, 1939, Serial No. 88,462

Term of patent 7 years

To all whom it may concern:

Be it known that I, Darrell E. Briner, a citizen of the United States and residing in Winchester, in the county of Randolph and State of Indiana,
have invented a new, original, and ornamental Design for a Whisky Flask, of which the following is a specification, reference being had to the accompanying drawing, forming a part thereof, wherein:

Figure 1 is a view in front elevation of a whisky flask, showing my new design;

Fig. 2 is a view in side elevation; and

Fig. 3 is a bottom plan view thereof.

I claim:

The ornamental design for a whisky flask, substantially as shown.

DARRELL E. BRINER.
